DESIGN FOR A COMBINED BILLFOLD AND COIN HOLDER

Louis Seamon, Brooklyn, N. Y.

Application February 1, 1940, Serial No. 89,929

Term of patent 3½ years

To all whom it may concern:

Be it known that I, Louis Seamon, a citizen of the United States, residing in Brooklyn, county of Kings, and State of New York, have invented a new, original, and ornamental Design for a Combined Billfold and Coin Holder, of which the following is a specification, reference being had to the accompanying drawing, forming part thereof.

Figure 1 is a plan view of a combined billfold and coin holder having a flap in covered position with the buttons in lowered position, showing my design; and

Figure 2 is a perspective view of the combined

billfold and coin holder shown in Figure 1 with the coin holder flap in open position and with the buttons in extended or raised position.

The back of the combined billfold and pocket coin holder is substantially plain.

The design for a combined billfold and pocket coin holder is characterized by the button coin holder with the flap thereon having the specific configuration shown.

I claim:

The ornamental design for a combined billfold and coin holder, as shown and described.

LOUIS SEAMON.
